WINCHESTER, MASSACHUSETTS.

SIGNALING APPARATUS.

1,138,543.

Specification of Letters Patent.

Patented May 4, 1915.

Application filed June 15, 1909. Serial No. 502,322.

To all whom it may concern:

Be it known that we, HERBERT C. DAVIS, a citizen of the United States, residing at New York, in the county and State of New York, and EVERETT D. CHADWICK, a citizen of the United States, residing at Winchester, in the county of Middlesex and State of Massachusetts, have invented certain new and useful Improvements in Signaling Apparatus, of which the following is a specification.

Our invention relates to apparatus for automatically giving an alarm or other signal in certain contingencies, and is particularly applicable to that class of apparatus which is used for determining whether night watchmen in factories and the like give proper attention to their duties. As adapted and employed for this purpose, our invention provides an arrangement which will automatically give one or more signals at a predetermined time or at periodic intervals unless, during a limited period preceding such time or each such interval, the watchman operates, as a part of his duty, a mechanism whereby the giving of such signal or signals will be prevented, so that the giving of a signal will show that the watchman has neglected his duty and may be utilized to call attention to that fact.

Our invention may be embodied in or adapted for use in connection with a variety of apparatus of the character above referred to, and is herein illustrated as embodied in a watchman's clock of that type which is customarily located in the office of a factory or the like and is provided with a push button intended to be operated by the watchman at the beginning of each of his periodic rounds through the factory, the result of each operation of the push button being that the time of doing so is registered by means of appropriate mechanism contained in the clock case.

In the accompanying drawings, which are largely diagrammatic in character and are not intended to illustrate all the details of commercial construction, Figure 1 is a front elevation, partly broken away, of a watchman's clock embodying our invention, and Fig. 2 is a detail view illustrating a slight modification.

Referring to Fig. 1 of the drawings, 2 indicates a watchman's clock comprising the usual time dial 3, time keeping mechanism

(not shown), a push rod 4 passing through the clock case and having a push button 5 on its outer end, and a spring 6 tending to hold said push rod in its outermost position. When the push button 5 is pushed inward a record of the time of doing so is made upon a rotating disk, which is located at 7. In practice the clock case is kept locked and cannot be opened without recording the time of doing so upon the disk, which disk, and the details of the mechanism for making the record upon it, are not illustrated in the drawings, as they may be of the usual or any suitable construction.

In connection with the parts just referred to, which are not original with us, we provide a signaling mechanism comprising, in the particular construction illustrated, a disk 8 which is continuously rotated by the clock mechanism and makes one complete rotation per hour, assuming that the watchman is supposed to make hourly rounds of the factory in which the clock is installed. For convenience of illustration this disk 8 is shown as mounted upon the arbor which carries the minute hand of the clock. The signals are preferably audible signals given by means of an electrically-operated bell or the like, and in such case the disk 8, or such portion thereof as may be necessary, is made of metal, being insulated from the clock mechanism by means of a hub 9 of hard rubber or other suitable material.

Adjacent to the disk 8 are located one or more contact terminals, according to the number of different signals to be given by the apparatus. In the drawings we have shown two such contact terminals, which are illustrated at 10 and 11 respectively, being severally mounted upon the clock case in fixed position and insulated therefrom. A contact projection 12 is formed or otherwise provided on the disk 8 in such position as to make contact with the terminals 10 and 11, one after the other, as the disk rotates, and in addition to these terminals 10 and 11 we provide another contact terminal 13 consisting of a metallic spring carried by a pivoted metallic arm 14 and constantly pressed toward the periphery of the disk 8 by a metallic spring 15 carried by and insulated from the clock case and bearing upon the arm 14. Provision is made for holding the terminal 13 out of contact with the disk 8, as for example by providing the arm 14 with a shoul-

der 16 adapted to be engaged by the notched end 17 of a pivoted, spring-actuated latch 18 when the lower end of said arm 14 is sufficiently moved to the left from the position shown in, Fig. 1. The opposite end of the latch 18 is located in position to be moved outward by a suitable projection carried by the disk 8, the contact projection 12 being conveniently employed for this purpose, and whenever such movement of the latch 18 takes place, the terminal 13 is immediately pressed into contact with the disk 8 by means of the spring 15. The terminal 13, arm 14 and latch 18 constitute what may be called an automatic setting device, by means of which the signal-operating circuit is put in condition to be subsequently closed, as hereinafter described.

Circuit wires 19 and 20 extend from the spring 15 and terminal 10 respectively to a battery 21, and an alarm device, such for example as an electric bell 22, is included in this circuit. Another circuit wire 23 leads from the terminal 11 through an alarm-giving device to the circuit wire 20 between the bell 22 and the battery 21, and as shown in Fig. 1 this alarm-giving device consists of a relay 24 included in the circuit wire 23 and itself adapted when the current passes through it to close a supplementary or outside circuit 25 which includes another electric bell 26. The bell 22 is intended to be placed within or upon the clock itself, or at any other convenient place within the factory in which the clock is located, while the bell 26 is likely to be located at some more distant point, for which reason the employment of the relay 24 and the outside circuit having its own battery is desirable. This bell 26 may be placed upon the outside of the factory building which contains the clock, or the circuit which operates this bell may be extended to the house of the superintendent or owner.

45 The arm 14 is so connected to the push button 5 that when the latter is pushed inward said arm is moved into position to be latched by the latch 18, the contact between the terminal 13 and the disk 8 being thereby broken. In the arrangement shown in the drawings this is accomplished by means of a lever 27 pivotally supported upon the clock case and forked at its lower end to straddle the rod 4 which carries the push button 5 at its upper end; said rod 4 being provided with pins 28 between which the lower end of the lever 27 passes, so that the inward and outward movements of the rod 4 will cause said lever to rock on its pivot, and the upper end of the lever 27 being located just in front of the lower end of the arm 14, as shown in Fig. 1.

As thus constructed, the operation is as follows. When the parts are in the position shown in Fig. 1, the projection 12 has just

passed the latch 18 and by turning said latch on its pivot has released the arm 14, and the contact terminal 13 carried by the latter arm has been pressed by the spring 15 into contact with the outer edge of the disk 8, so that the electric circuit between the disk 8 and the battery 21 through the terminal 13, arm 14 and spring 15 is complete. After the parts have assumed this position a certain interval will elapse, depending upon the relative position of the latch 18 and the terminal 10, during which interval the watchman is supposed as a part of his regular duty to press the push button 5 inward and thereby register the time of doing so upon the recording disk, this being the time at which he is supposed to start upon one of his hourly rounds through the factory. If the watchman is attending to his duties and operates the push button 5 as required, the inward movement of the rod 4 will rock the lever 27 on its pivot and thus cause the upper end of this lever to move the lower end of the arm 14 to the left until it is engaged and locked by the spring latch 18, thus breaking the contact between the terminal 13 and the disk 8. At the expiration of the interval above referred to the projection 12 will make contact with the spring terminal 10, and if the watchman has duly operated the push button 5 no alarm will be given, since the circuit through the bell 22 will be broken at the terminal 13. If, however, the watchman has failed to operate the push button 5 the terminal 13 will remain in contact with the disk 8, and therefore, as soon as the projection 12 touches the terminal 10, the circuit through the bell 22 will be closed and said bell will ring, thus drawing the attention of the watchman to his failure to operate the push button 5. If he now operates the push button the arm 14 will be moved to the left and latched, and the circuit will thereby be broken, but if he fails to do this within another interval depending upon the distance between the spring terminals 10 and 11, then as soon as the projection 12 touches the terminal 11 the circuit will be closed through the relay 24 and said relay will thereupon close the circuit through the bell 26, thus giving a supplementary alarm by means of the latter bell. This alarm will continue to be given as long as the projection 12 remains in contact with the terminal 11, and this terminal is purposely made long enough to preserve the contact at this point for a considerable interval, say five or ten minutes, or longer if desired, to insure the effectiveness of the alarm given by means of the bell 26. At any time during the maintenance of the contact between the projection 12 and the terminal 11 the circuit through the relay may be broken by operating the push button 5, whereupon the circuit through the bell 26 will also be broken and the bell 123

will stop ringing. This bell will also stop ringing in any event as soon as the projection 12 passes out of contact with the terminal 11, and no further alarm can be given until said projection reaches the terminal 10.

It will be seen that the arm 14 will always be unlatched at the beginning of the period during which the watchman is supposed to operate the push button 5, so that each 10 operation of the push button must take place within the required interval in order to prevent the giving of an alarm, regardless of the operation of the push button at any other time; in other words, it is impossible 15 for the watchman to operate or set the mechanism in any way which will prevent the giving of an alarm unless he does this during the intended period above referred to.

In the modified arrangement shown in 20 Fig. 2 the arm 14 and latch 18 are replaced by a single pivoted arm 29, one end of which is arranged to be operated by the projection 12 and the other end of which carries a 25 spring contact terminal 30, said arm 29 being actuated by the upper end of the lever 27 as above described. A spring 31 mounted on an insulated support and connected to the battery circuit is provided with depressions adapted to coöperate with a pin 32 projecting laterally from the arm 29 in such manner that when the projection 12 30 throws the upper end of the arm to the left, thereby pressing the terminal 30 into contact with the disk 8, the pin 32 will be 35 located in the left hand depression in the spring 31, while when the lower end of the arm 29 is forced to the left by the rocking of the lever 27 the pin 32 will enter the right hand depression in the spring, which 40 thus serves to hold said arm in either of the positions above referred to but permits it to be easily shifted to the other position either by means of lever 27 or by means of the projection 12. In this arrangement 45 the circuit when closed passes through the disk 8, terminal 30, arm 29, pin 32 and spring 31, the construction and arrangement of the remaining parts being as shown in Fig. 1.

The arrangement shown in Fig. 2 is somewhat simpler than that shown in Fig. 1, but in some cases may be less desirable for this reason, that while the upper end of the arm 29 is resting upon the projection 12 the push 55 button 5 cannot be operated, because the upper end of the lever 27 will be prevented by the lower end of the arm 29 from moving to the left, so that for a short period it will be impossible to record upon the disk an attempt 60 operation of the push button 5. With the construction shown in Fig. 1, however, the push button 5 can be operated and a record made upon the disk at any time.

It will be understood that the location of 65 the latch 18 and the contact terminals 10

and 11 will be determined in accordance with the intervals which it is desired to allow to the watchman for operating the push button, which intervals may be varied as desired. For example, assuming that the 70 watchman is supposed to start on a round at the beginning of each hour, as is customary, the latch 18 may be so located as to be tripped at ten minutes before the hour, the terminal 10 may be so located as to 75 make contact with the projection 12 at five minutes before the hour, and the terminal 11 may be so located as to make its initial contact with the projection 12 on the hour, but the times of tripping the latch and making 80 the electrical contacts, and also the number of these contacts, may be varied as desired, and any suitable form of device for giving an alarm or other signal may be used and may be located at whatever point 85 may be thought desirable. It will be observed that the parts 10, 11, 13 and 18 remain wholly out of contact with the disk 8 and its projection 12 throughout the greater 90 part of the period of rotation of the disk, 95 so that the frictional resistance to the rotation of the disk and therefore the additional work imposed upon the clock mechanism are reduced to a minimum. The employment of electrically-operated alarm-giving 95 devices is not essential, however, and the several details of construction and arrangement may be widely varied without departing from our invention, as will be evident.

We claim as our invention:—

1. An apparatus of the character described, comprising an electric signaling circuit including a contact terminal, manually-operative means for breaking said circuit during a predetermined interval, and periodically-operating means for automatically resetting said circuit-breaking means at the beginning of said interval and for closing the signaling circuit at said contact terminal at the end of said interval. 100

2. An apparatus of the character described, comprising an electric signaling circuit which is normally open at two different points, periodically-operating means for automatically closing the circuit at said 110 points at the beginning and end of a predetermined interval, respectively, and manually-operative means for breaking the circuit during said interval.

3. An apparatus of the character described, comprising an electric signaling circuit having two normally-open branches and signaling mechanisms included in said branches respectively, the common portion of said circuit being normally open at a 120 different point, periodically-operating means for automatically closing said circuit at the latter point and for thereafter closing the branch circuits in succession at the ends of predetermined intervals; and manually- 125

operative means for opening the common portion of said circuit during said intervals.

4. The combination with a watchman's 5 clock of an electric signaling circuit, said circuit being normally open at two different points, means operated by the clock mechanism for periodically closing the circuit at said points successively, and a device adapt- 10 ed to be manually operated from the exterior of the clock for breaking said circuit during the intervening period.

5. The combination with a watchman's 15 clock of a normally-open electric signaling circuit having two distant contact terminals in series therein, means operated by the clock mechanism for closing the circuit through said terminals successively at periodic intervals, and means operative from the exterior 20 of the clock for breaking the circuit through one of the terminals prior to the closing of the circuit through the other terminal.

6. In a watchman's clock, the combination 25 with a time mechanism, and a recording mechanism adapted to be operated from the exterior of the clock case, of a signaling mechanism arranged to be operated by the time mechanism at periodic intervals, a setting device therefor, said setting device being operated by said time mechanism prior to the giving of a signal, and connections between the recording mechanism and the setting device for operating the latter to prevent 30 the giving of a signal.

7. An apparatus of the character described, comprising a disk provided with a contact projection and means for rotating the same, one or more contact terminals 40 located in position to be engaged by said projection as the disk rotates, an electric signaling circuit including said disk, projection and terminals, a supplementary contact terminal included in said circuit and means 45 tending to hold the same in contact with said disk, means for moving the latter terminal out of contact with the disk, a latch to hold the latter terminal out of contact with the disk, and means operated by the 50 rotation of the disk for tripping said latch.

8. An apparatus of the character described, comprising a rotating disk having a contact projection, one or more contact terminals located in the path of said projection, a supplementary contact terminal 55 movable into and out of contact with the

disk, means for moving the latter terminal out of contact with the disk, a latch to hold said terminal in such position, said latch being located in position to be tripped 60 by the contact projection on the disk prior to the engagement of said projection with the first-mentioned contact terminal or terminals, and an electric signaling circuit leading through said contact terminals, projection and disk. 65

9. In a watchman's clock, the combination with a time mechanism, a recording mechanism, and a push button for operating the same, of a disk continuously rotated by the 70 clock mechanism and having a contact projection, one or more contact terminals located in the path of said projection, a supplementary contact terminal and means tending to move the same into contact with the disk, connections between said push button and supplementary terminal to move the latter out of contact with the disk, a latch to hold the latter contact terminal in such position, means operated by the rotation of 80 the disk for tripping said latch, and an electric signaling circuit leading through said contact terminals, disk and contact projection.

10. In a watchman's clock, the combination with a time mechanism, a recording mechanism, and a push button for operating said recording mechanism, of a disk rotated by the clock mechanism and having a contact projection, two contact terminals located in position to be engaged successively by said projection when the disk rotates, a supplementary contact terminal and means for pressing the same against the disk, a latch to hold the latter terminal out of contact with the disk, connections between said supplementary terminal and the push button for moving the former into latching position, an electric signaling circuit connecting the supplementary contact terminal with each of the other contact terminals, and means carried by the disk for tripping said latch prior to the closing of the circuit through the first contact terminal. 95

In testimony whereof, we have hereunto 100 subscribed our names this eleventh day of June, 1909.
